STRUCTURAL TOWER

Theodore Bowman Fleming, Princeton, Ind., assignor to Blaw-Knox Company, Blawnox, Pa., a corporation of New Jersey

Application October 29, 1931. Serial No. 571,755

15 Claims. (Cl. 189—33)

This invention relates generally to structural towers for supporting transmission lines, such as high tension power lines, telephone and telegraph wires, and more particularly to a broken conductor load release whereby the pull on a wire, due to breakage of a wire in an adjoining span, is transferred from the end of the cross arm to the tower.

In the accompanying drawings, which illustrate several embodiments of my invention,

Figure 1 is an elevation of a structural tower illustrating the broken conductor load release;

Figure 2 is a horizontal section taken in a plane corresponding to the line II—II of Figure 1;

Figure 3 is an elevation of a portion of the tower and cross arm illustrating a different type of load release;

Figure 4 is a plan view of the structure illustrated in Figure 3 illustrating the action of the load release after a wire has been broken in an adjoining span;

Figure 5 is a detail perspective view of the load release illustrated in Figures 3 and 4;

Figures 6, 7 and 8 are, respectively, a side elevation, an end elevation partly in section, and a bottom plan view of a modified type of load release;

Figures 9 and 10 are, respectively, a side elevation and an end elevation of another form of load release;

Figures 11 and 12 illustrate in side elevation two other modifications of load releases; and

Figure 13 illustrates a telescoping tie rod which may be used for connecting the insulator hanger with the tower.

Wires are generally supported at the ends of the cross arms of a structural tower. If a wire breaks due to the wind or the accumulation of snow or sleet thereon, it creates excessive pull in the spans adjoining the broken wire. This excessive pull is transmitted through the cross arm to the tower, thereby tending to break the cross arm or subject the tower to too great torsional effects.

In accordance with the present invention, the wires are supported from strings of insulators which are hung from an insulator hanger. The insulator hanger is detachably supported by a support rigidly secured to the cross arm. The support is of such shape, for example a hook shape, that under normal conditions the insulator hanger is supported by the support secured to the cross arm. However, if a wire breaks, thereby increasing the tension in an adjoining span, the increased tension causes the insulator hanger to slide from engagement with its support. The insulator hanger, in addition to being detachably connected to its support, is pivotally connected by a tie rod or other means to the tower so that when the insulator hanger slips from its support,

the tie rod swings into the direction of the wire, and the tension is transferred to the tower. The length of the tie rod is added to the length of the unbroken span of wire, thereby decreasing the tension on the wire.

Referring more particularly to Figures 1, 2, 6, 7 and 8 of the accompanying drawings, there is shown a structural tower 2 having cross arms 3, from which the wires 4 are supported. Each of the wires 4 is supported from a string of insulators 5 suspended from an insulator hanger 6. The insulator hanger is detachably supported by a support 7 secured to the underside of the cross arm 3. The insulator hanger 6 is also pivotally connected by means of a tie rod 8 to the tower 2.

Figures 6, 7 and 8 illustrate in detail the construction of the load release. Referring to these figures, the cross arm has at its outer end a support 7 which is hook shape in cross section. This support comprises a leg 10 welded or otherwise secured to the bottom of the cross arm 3, and a flat vertically extending portion 11. At the bottom of the portion 11, the plate is curved inwardly to form a vertically extending flange 12. The insulator hanger 6 is formed with a hook 14 which fits over the flange 12 of the support 7. As shown in Figures 6 and 7, the support 7 extends in the direction of the wire, and the flange 12 is curved so that its center 15 is lower than its ends 16. The hook 14 of the insulator support normally is in the position shown in Figure 7, but when undue stress is placed on the wire, it slips off from the end of the flange 12, as hereinafter described. The hook 14 is pivotally connected to the forked end of the tie rod 8, as indicated by the reference numeral 18, and the tie rod is pivotally connected at its other end to the tower 2. This pivotal connection may be made, as illustrated in Figures 6, 7 and 8, by passing a U-bolt 19 through the eye of the tie rod 8 and securing the U-bolt to an angle 20 secured to the tower.

Figures 3, 4 and 5 illustrate the action of the load release when a wire breaks. The support for the insulator hanger is of a slightly different construction than that just described. In these figures, parts corresponding to those previously described are designated by the same reference numerals with the letter *a* suffixed. The support for the insulator hanger 6a is shown in detail in Figure 5, from which it will be seen that the insulator hanger fits over a channel section 7a which is welded to an angle 10a secured to a plate 21, which in turn is secured to the cross arm 3a. The channel support 7a extends in the direction of the wire and, as shown in Figure 5, it is curved longitudinally so that if the tension in the wire increases to a sufficient extent, the hook 6a will slide off the end of the channel support 7a. If the wire 4a breaks at the point A

shown in Figure 4, it will cause increased tension on the span B of the wire. This increased tension is transmitted through the insulators to the insulator hanger 6a so as to cause the insulator hanger to slide off the end of its support. The tie rod 8a then swings from its dotted-line position to the full-line position illustrated in Figure 4 so as to add its length to the length of the span of wire. This decreases the tension on the span and, in addition, since the tie rod is pivoted to the tower as indicated at 19a, the reduced stress is transmitted to the tower itself, instead of being applied to the end of the cross arm. This decrease leverage results in a decrease in the torsional effect on the tower.

In Figures 9 and 10 there is illustrated another modification of the load release in which the support 7b has a leg 10b secured to the cross arm 3. The vertical leg 11b is provided with a flange 22 at its lower edge. This flange extends in the direction of the wire and is curved, as indicated in Figure 10, so that the insulator hanger 6b may slide off the end when a span of wire is under sufficient tension. The insulator hanger 6b is provided with two hook portions 23 which fit over the flange 22. The insulator hanger is pivotally connected to the tower by means of a tie rod 8b in a manner similar to that described in connection with the other modifications. The insulator hanger is provided with an opening 25b corresponding to openings 25, 25c, 25d in other modifications, for connecting the string of insulators thereto. When sufficient tension is exerted upon one span of the wire, the insulator hanger 6b slips from the end of the flange 22, as previously described.

In Figure 11 there is illustrated another embodiment in which the insulator hanger 6c is hung from two supports 7c. The insulator hanger extends transversely of the direction of the wire and is pivotally connected to the tower by a tie rod 8c. One leg 10c of each of the supports 7c is secured to the cross arm 3 and the other leg or web 11c has a flange 22c formed at its lower edge. The construction of each of the supports 7c is the same as shown in Figures 9 and 10. The supports 7c are spaced longitudinally of the cross arm so as to prevent the insulator hanger from swinging in a direction transverse to the wire. All of the transverse motion takes place in the string of insulators which may be connected to the insulator hanger by a pin (not shown) extending through the opening 25c. There are cases where this construction is of advantage in that it permits greater deflection of the insulator string transverse to the direction of the wire.

In Figure 12 there is shown a still further modification in which each of the plates 7d, which together form the support for the insulator hanger 6d, is provided at its lower edge with a flange 22d extending toward the flange on the corresponding plate 7d. The flanges 22d are curved in a similar manner to the flange 22 shown in Figure 10, and together form a supporting surface for supporting the insulator hanger. The insulator hanger is pivotally connected to the supporting tower by a tie rod 8d.

In Figure 13 there is shown a telescoping tie rod which may be used in place of the tie rod shown in any of the embodiments previously described. The tie rod is made in two parts 27 and 28, the part 27 passing through a loop 29 formed in the part 28 and the part 28 passing through a loop 30 formed in the part 27. It ordinarily is not necessary to employ the telescoping tie rod

since the ordinary one-piece tie rod adds sufficient length to the span of wire after the insulator hanger has slid off from its support and the tie rod has swung into the direction of the wire. The effective length of the tie rod may, however, be increased by using a telescoping tie rod of the type shown, or other type extensible tie rod, so as to increase the effective length of the tie rod which is added to the span of wire in order to still further decrease the pull on the span.

In certain embodiments, for example those shown in Figures 9, 10 and 11, a wooden bar is used in place of the metal tie rod for pivotally connecting the insulator hanger to the tower. Either wood or metal tie rods may be used in any of the embodiments, the wooden tie rod having the advantage of adding materially to the insulating properties of the hanger, although being weaker than the metal tie rod. In place of using a rigid tie rod, a chain may be employed for connecting the insulator hanger to the tower, but this ordinarily is not as desirable as a rigid tie rod, since the chain hangs down below the cross arm and occupies some of the space which it is desirable to have free for the movement of the wire 4, so that there will be no danger of arcing or short-circuiting.

In each of the embodiments described, when sufficient pull is exerted on the wire due to the breakage of the wire in an adjoining span, the insulator hanger slips off the end of its support without breakage of any of the parts, and the tie rod or other means connecting the insulator hanger with the tower swings into the line of the wire, thereby adding its length to the length of the span and transferring the pull of the wire from the end of the cross arm to the tower.

I have illustrated and described several embodiments of my invention. It is to be understood, however, that the invention may be otherwise embodied within the scope of the following claims.

I claim:

1. In a structural tower having a cross arm adapted to support a wire, a curved support which is lower at its center than at its ends secured to the cross arm, an insulator hanger detachably connected to and supported by said support when the wire is under normal tension but adapted to slip off said support when the wire is under abnormal tension, and means pivotally connecting the insulator hanger with the tower, whereby said means may swing into the direction of the wire after the insulator hanger has slipped off from its support due to breakage of the wire in an adjoining span.

2. In a structural tower having a cross arm adapted to support a wire, a curved hook-like support which is lower at its center than at its ends secured to the cross arm, an insulator hanger detachably connected to and supported by said support when the wire is under normal tension but adapted to slip off said support when the wire is under abnormal tension, and means pivotally connecting the insulator hanger with the tower, whereby said means may swing into the direction of the wire after the insulator hanger has slipped off from its support due to breakage of the wire in an adjoining span.

3. In a structural tower having a cross arm adapted to support a wire, a curved hook-shape support which is lower at its center than at its ends secured to the cross arm, a hook-shape insulator hanger detachably connected to and supported by said support when the wire is under normal tension but adapted to slip off said support when

- the wire is under abnormal tension, and means pivotally connecting the insulator hanger with the tower, whereby said means may swing into the direction of the wire after the insulator hanger has slipped off from its support due to breakage of the wire in an adjoining span. 5
4. In a structural tower having a cross arm adapted to support a wire, a curved support secured to the cross arm and extending in the direction of the wire, an insulator hanger detachably connected to and supported by said support when the wire is under normal tension but adapted to slip off said support when the wire is under abnormal tension, said support being lower at its center than at its ends, the ends of said support being open, and means pivotally connecting the insulator hanger with the tower, whereby said means may swing into the direction of the wire after the insulator hanger has slipped off from its support due to breakage of the wire in an adjoining span. 10
5. In a structural tower having a cross arm adapted to support a wire, a support secured to the cross arm, an insulator hanger detachably supported by said support, and a tie rod pivotally connecting the insulator hanger with the tower, said tie rod being extensible, whereby said tie rod may increase in length and swing into the direction of the wire after the insulator hanger has slipped off from its support due to breakage of the wire in an adjoining span. 15
6. In a structural tower having a cross arm adapted to support a wire, a support secured to the cross arm, an insulator hanger detachably supported by said support, a tie rod having telescoping portions, one portion being connected to the insulator hanger and another portion being pivotally connected to the tower, whereby the tie rod may increase in length and swing into the direction of the wire after the insulator hanger has slipped off from its support due to breakage of the wire in an adjoining span. 20
7. In a structural tower having a cross arm adapted to support a wire, a support secured to the cross arm, said support extending in the direction of the wire and being hook shape in transverse section, a hook-shape insulator hanger detachably connected to and supported by said support when the wire is under normal tension but adapted to slip off said support when the wire is under abnormal tension, the surface of said support engaged by said insulator hanger being lower at the center than at the ends, and a tie rod pivotally connecting the insulator hanger with the tower, whereby said tie rod may swing into the direction of the wire after the insulator hanger has slipped off from its support due to breakage of the wire in an adjoining span. 25
8. In a structural tower having a cross arm adapted to support a wire, a plurality of supports spaced longitudinally of and secured to the cross arm, an insulator hanger extending transverse to the direction of the wire and detachably supported by said supports, a tie rod pivotally connecting the insulator hanger with the tower, whereby said tie rod may swing into the direction of the wire after the insulator hanger has slipped off from its supports due to breakage of the wire in an adjoining span. 30
9. In a structural tower having a cross arm adapted to support a wire, a support extending in the direction of the wire and secured to the cross arm, said support having a flange at its lower edge, the flange curving upwardly toward its ends, an insulator hanger detachably connected to and supported by said support when the wire is under normal tension but adapted to slip off said support when the wire is under abnormal tension, and means pivotally connecting the insulator hanger with the tower, whereby said means may swing into the direction of the wire after the insulator hanger has slipped off from its support due to breakage of the wire in an adjoining span. 35
10. In a structural tower having a cross arm adapted to support a wire, means for detachably supporting the wire from the cross arm, and other means arranged below the cross arm and pivotally connecting said first mentioned means with the tower, whereby said other means may swing into the direction of the wire after the first mentioned means has been detached from the cross arm due to breakage of the wire in an adjoining span. 40
11. In a structural tower having a cross arm adapted to support a wire, means for detachably supporting the wire from the cross arm, a tie rod arranged below the cross arm and pivotally connecting said first mentioned means with the tower, whereby said tie rod may swing into the direction of the wire after the first mentioned means has been detached from the cross arm due to breakage of the wire in an adjoining span. 45
12. In a structural tower having a cross arm adapted to support a wire, an insulator hanger detachably supported from the cross arm, a tie rod arranged below the cross arm and pivotally connecting said insulator hanger with the tower, whereby said tie rod may swing into the direction of the wire after the insulator hanger has been detached from the cross arm due to breakage of the wire in an adjoining span. 50
13. In a structural tower having a cross arm adapted to support a wire, means for detachably supporting the wire from the cross arm, and other means arranged below the cross arm and pivotally connecting said first mentioned means with the tower, whereby said other means may swing into the direction of the wire after the first mentioned means has slipped off from its support with the cross arm due to breakage of the wire in an adjoining span. 55
14. In a structural tower having a cross arm adapted to support a wire, a support secured to the cross arm, an insulator hanger detachably supported by said support, and means arranged below the cross arm and pivotally connecting the insulator hanger with the tower, whereby said means may swing into the direction of the wire after the insulator hanger has been detached from its support due to breakage of the wire in an adjoining span. 60
15. In a structural tower having a cross arm adapted to support a wire, a support secured to the cross arm, an insulator hanger detachably supported by said support, and a tie rod arranged below the cross arm and pivotally connecting the insulator hanger with the tower, whereby said tie rod may swing into the direction of the wire after the insulator hanger has slipped off from its support due to breakage of the wire in an adjoining span. 65
